CLAIM

The ornamental design for an insulated bottle cover, as shown and described.

DESCRIPTION

FIG. 1 is a diagrammatic perspective view of the insulated bottle cover in full lines with a bottle shown in broken lines representing environmental association matter being for illustrative purposes only and forming no part of the claimed invention.

FIG. 2 is a front elevational view thereof.

FIG. 3 is a rear elevational view thereof.

FIG. 4 is a top plan view thereof.

FIG. 5 is a bottom plan view thereof.

FIG. 6 is a left side elevational view thereof; and,

FIG. 7 is a right side elevational view thereof.
